UNITED STATES PATENT OFFICE

CARL ULTES, OF SPRINGFIELD, OHIO, ASSIGNOR TO THE O. S. KELLY COMPANY, OF SPRINGFIELD, OHIO, A CORPORATION OF OHIO

DESIGN FOR A GASOLINE DISPENSING PUMP

Application filed December 24, 1932. Serial No. 46,580. Term of patent 7 years.

To all whom it may concern:

Be it known that I, CARL ULTES, a citizen of the United States, residing at Springfield, in the county of Clark and State of Ohio, have invented a new, original, and ornamental Design for a Gasoline Dispensing Pump, of which the following is a specification, reference being had to the accompanying drawing, forming part thereof.

Fig. 1 is a front perspective and Fig. 2 is a top plan of the casing only of a gasoline dispensing pump showing my new design.

I claim:

The ornamental design for a gasoline dispensing pump, as shown.

CARL ULTES.
